UNITED STATES PATENT OFFICE

2,679,703

ROTARY WHEEL DITCHING MACHINE

Walter A. Borel, New Iberia, La.

Application November 27, 1950, Serial No. 197,807

2 Claims. (Cl. 37—92)

1

The present invention relates to new improvements in ditching machines, and more particularly to the type of ditching machine which may be manually manipulated to dig ditches.

An object of the present invention is to provide a novel ditching machine wherein rotary blades are provided for scooping dirt to form a ditch.

A further object of the present invention resides in the provision of a common means for driving a driving roller and the ditching mechanism, whereby the ditching machine may be moved forwardly while the rotary blades dig the ditch.

Still another object of the present invention resides in the provision of means for selectively disengaging either the ditching means or the driving roller from the common driving means whereby the machine may be moved forwardly without digging or may remain stationary while digging at a selected spot.

A still further object of the present invention resides in the provision of a novel guard plate whereby the dirt discharged from the rotary blades will be diverted from the driving means and will be directed to one side of the machine.

Another object of the present invention resides in the provision of a novel guide means whereby the ditch will be dug along a substantially straight line.

Still another object of the present invention resides in the provision of a novel resilient mounting means at the rear end of the frame of the machine whereby the forward end may be resiliently raised or lowered by manipulation of the handles of the frame.

A still further object of the present invention resides in the provision of novel adjustable supporting wheels and adjustable caster wheels, the first-mentioned supporting wheels being provided for use while transporting the ditching machine from one place to another when not ditching, and also to ride along the surface of the ground adjacent to the ditch while ditching, while the second pair of wheels, the caster wheels, are provided for running along the bottom of the ditch for supporting the forward end and aiding in the determination of the depth of the ditch.

Various other objects and advantages will become apparent from the detailed description to follow. The best form in which I have contemplated applying my invention is clearly illustrated in the accompanying drawings, wherein:

Figure 1 is a side elevational view of the ditching machine while digging a ditch;

2

Fig. 2 is a front elevational view of Figure 1; Figure 3 is a rear elevational view of Figure 1; Figure 4 is a top plan view of the forward portion of the ditching machine;

Figure 5 is a side elevational view of a portion of the machine adjacent the forward end showing the ditching means and the drive pulley arrangement therefor;

Figure 6 is a detail sectional view of the clutch means employed in connection with the present invention; and

Figure 7 is a side elevational view of the entire machine when being transported from one place to another.

Referring more particularly to the drawings, wherein like numerals designate like parts throughout, the ditching machine of the present invention comprises a frame designated by the numeral 12. The numeral 14 designates generally an internal combustion engine mounted on the frame means 12 and providing a common source of power for driving the machine. The ditching machine also comprises a resilient mounting means for the rear end of the frame 12 designated by the numeral 16, a transverse driving traction roller means 18 intermediate the ends of the frame 12 supporting wheels 20 in front of said roller means 18, caster wheels in front of wheels 20 for the forward end of the frame 12 as at 22, a ditching means 24 in front of the caster wheels 22, and a guard means 26 for the ditching means 24 located above the same.

The frame 12 comprises a pair of longitudinally extending angle irons 28 and 30 which are joined at their rear ends by a transversely extending bar 32. A pair of angulated bars 34 and 35, respectively, extend upwardly and rearwardly from the forward ends of the angle irons 28 and 30 and are joined adjacent their rear ends by means of the angle iron 36 which is disposed substantially in parallel relation to the bar 32 and lies in the same vertical plane as the bar 32. The outer ends of the bars 34 and 35 are angulated at 40 and 42 to provide handles.

The resilient mounting means 16 for supporting the rear end of the frame 12 comprises a standard 44 which is reciprocably disposed through a pair of sleeves 46 and 48, the sleeve 46 being integrally secured to the angle iron 36 while the sleeve 48 is integrally formed with the bar 32 in axial alignment with the sleeve 46. The standard 44 is provided with an annular ring 50 disposed below the sleeve 46 and a coil spring 52 encircles the standard 44 and has one end abutting the ring 50 while the other end abuts the

bottom portion of the sleeve 46 for normally urging the standard in a downward direction. The lower end of the standard 44 is provided with a caster wheel 54 of conventional form.

The internal combustion engine 14 is disposed centrally of the frame 12 and is mounted on the base 58 supported by the longitudinally extending angle irons 28 and 30. The internal combustion engine 14 has a drive shaft 60 extending longitudinally of the frame 12 both forwardly and rearwardly of the internal combustion engine. At opposite ends of the shaft 60 internally beveled friction clutch disks 62, 64 are provided each having a beveled recess 64, 63 respectively.

At the forward end of the frame 12 a supporting plate 66 is provided which is substantially of inverted U-shape in cross-section with the end portions thereof angulated for engagement with the upper surfaces of the angle irons 28 and 30 whereby the plate 66 may be secured thereto, providing a supporting means for the bearing 68. A shaft 70 having a pulley 72 secured thereto is mounted for rotative and reciprocal movement in the bearing 68 and is in axial alignment with the shaft 60. As seen best in Figure 6 again, the shaft 70 is provided with a clutch disk 74 at the end adjacent to the shaft 60, the clutch disk 74 having a beveled surface 76 for engagement with the beveled surface of the recess 64. The shaft 70 has a reduced diameter portion 78 which is received in a recess 79 in the end of the shaft 60 whereby the two shafts may be maintained in alignment, facilitating engagement and disengagement of the two clutch elements.

The clutch disk 74 is keyed, as at 75, to the shaft 70 and is adapted to reciprocate thereon for engagement with the clutch element 62. The clutch disk 74 has an elongated sleeve 80 extending rearwardly therefrom and terminating in a disk 82 having a recess 84 of annular form. A ring 86 is received around the disk 82 and has radial projections 88 received in the annular recess 84 whereby longitudinal movement of the ring 86 will effect longitudinal movement of the clutch disk 74 into and out of engagement with the clutch element 62.

The ring 86 is integrally formed with a downwardly extending lever 90 which is pivotally mounted, as seen at 91, on the upper end of a bar 92 upstanding from and secured to the angle iron 94, the angle iron 94 being mounted on the frame 12 and extending transversely thereof. The upper end of the ring 86 is connected to the shaft 96 which is in turn pivotally connected, as at 97, to the rearwardly extending bar 98 terminating in the handle 100. An upstanding bracket element 102 on the rods 34, 35 and provided with an eyelet 104 at its upper end reciprocably maintains the bar 98 in supported relation with respect to the handle rods 34 and 36. Keeping in mind the loose connection between the ring 86 and its radial projections 88 and the recess 84, it will readily be seen that reciprocation of the handle 100 will effect longitudinal movement of the clutch disk 74 into and out of engagement with the recess 64 for conveying rotary movement from the drive shaft 60 to the shaft 70 and pulley sheave 72 secured thereto.

As seen best in Figure 5, a plate 106 connects the angle irons 28 and 30 at the front ends thereof and a pair of bearing brackets 108 and 110 are secured to the under side of the plate 106 by means of the bolts 112. A stub shaft 114 is rotatably disposed longitudinally of the frame 12 in

the bearing elements 108 and 110 and has a pulley sheave 116 secured to its inner end and lying in the same plane as the pulley sheave 72. A belt 118 extends over the pair of pulley sheaves 72 and 116 for conveying rotary movement from the shaft 70 to the shaft 114.

The outer end of the shaft 114 has a substantially circular disk 120 secured thereon by means of the nuts 122. The plate 120 is provided with a plurality of arcuately contoured blades 124 which effect the ditching operation.

The caster wheels 22 are disposed on opposite sides of the forward end of the frame 12. Attaching bars 126 for the caster wheels 22 are provided with vertically extending elongated slots 128. Securing bolts 130 extend outwardly from the angle irons 28 and 30 and are received in the slots 128. Nuts 132 are received on the bolts 130 for adjustably securing the caster wheels 22 in desired vertical relation to the frame.

The guard plate means 26 comprises an enlarged sheet metal plate 134 which is secured to the transversely extending bar 106 at the forward end of the frame. The upper end of the plate 134 is provided with a horizontally extending deflecting plate 136 to deflect the dirt. An extension 138 of the plate 134 which has its uppermost edge in angular relation to the upper edge of the plate 134 is similarly formed with a deflecting plate 140 which is in angular relation to the plate 138 to deflect the dirt from the frame and driving means of the ditching machine.

The supporting caster wheels 20 are of substantially conventional form, and are disposed on opposite sides of the frame 12. The upstanding shanks 141 of the wheels 20 are rotatably received in the bearing brackets 142 which have inwardly extending bars 144 terminating in downwardly extending attaching elements 146. The attaching elements 146 are provided with elongated slots, as shown at 147 in Figure 1, whereby they may be adjustably secured to the angle irons 28 and 30 by means of the bolts 148 for vertical adjustment of said caster wheels 20.

Centrally disposed on the under side of the frame 12 is the driving roller 18 which is mounted on a pair of supporting bearings 150 which are secured to the under side of the angle irons 152 and 154, which are in turn welded to the angle irons 28 and 30 respectively. The roller 18 is of heavy construction and is provided with ridges 156 on its outer surface for engagement with the surface of the ground to effect forward movement of the frame and ditching means when driven by the means now to be described.

As seen best in Figure 1, a gear box 158 is supported on the frame 12 and pulleys 160 and 162 connected by the belt 164 transfer power through a shaft 161, like the shaft 70, from the shaft 60 to the shaft 166 of the gear box 158. The gear box 158 is provided with a gear shift 168 and a pulley 170 at one side for driving the belt 172 and the pulley 174 of the roller means 18. It should be noted here that means are provided for engaging and disengaging the clutch disk 74' on the shaft 161, with respect to the clutch disk 61, the means being similar in construction to that shown in Figure 6 and hereinabove described. A lever 176 is provided for reciprocating the ring 86' corresponding to ring 86 for longitudinally moving the shaft 161 and clutch disk 74' into and out of engagement with the recess 63 in the clutch element 61, whereby movement may be selectively imparted to the gear box 158 and driving roller 18 when desired in a manner similar to that used

for imparting movement to the ditching machine.

Adjacent the forward end of the frame 12 is a guide means 180 which has its upstanding portion 182 secured to and depending from the bar 94. Guide means 180 includes a longitudinally extending angulated blade portion 184 in axial alignment with the ditching machine which is provided with a sharp edge blade 186 for engagement with the bottom of the ditch to provide substantially straight movement of the ditching machine.

From the foregoing description, taken in conjunction with the drawings, it is believed that the operation of the present invention will be readily obvious to one skilled in the art. When it is desired to operate either the driving roller means 18 or the ditching means 24, or both, the clutches are engaged and disengaged as desired by means of the levers 100 and 176. The forward speed of the machine may be controlled by the gear shift lever 168. When it is desired to dig a ditch, the supporting wheels 20 are raised for engagement with the supporting surface adjacent to the ditch to be dug. In other words, the supporting wheels 20 are fixed in raised relation to the driving roller 18, as will be readily apparent. Next, the wheels 22 are adjusted for engagement with the ground and to give the proper angular relation of the frame 12 with respect to the ground so that the cutting means or digging means 24 will engage the ground to dig the ditch. By manipulation of the handles 40 and 42 upwardly or downwardly, the machine may be tilted vertically about the axis of the driving roller 18 so that the forward end of the frame 12 may be raised or lowered, thus riding the ditching machine out of the ditch and back to digging when desired with the coil spring 52 assisting in lowering said forward end. When it is desired to transport the ditching machine, the supporting wheels 20 are lowered to the position shown in Figure 7 so that the entire machine will be supported by the wheels 20, the driving roller 18 and the rollers 54.

Having thus described my invention, what is claimed to be new is:

1. A ditching machine comprising a frame having front and rear ends, a ground engaging traction roller supporting said frame intermediate its ends for vertical tilting of the frame about the axis of the roller to raise and lower the front end of the frame, handles extending rearwardly from said frame for tilting the same, a rotary ditch digging element mounted on the front end of the frame in the longitudinal axis of the frame for lowering and raising into and from digging position by raising and lowering of said front end of the frame, a first pair of caster wheels depending from said frame between said element and roller and upon opposite sides of the axis of rotation of said element for traveling in the ditch to determine the depth to which said element shall dig, a second pair of caster wheels mounted on opposite sides of said frame in advance of said roller and vertically adjustable to maintain said front end of the frame tilted upwardly sufficiently to raise said element and first pair of caster wheels above the ground into idle position, and means for driving said roller and element.
2. A ditch digging machine according to claim 1, said second pair of caster wheels being spaced apart a greater distance than the width of the ditch dug by said element for adjustment into engagement with the surface of the ground at opposite sides of the ditch to maintain said front end tilted upwardly.
